Specification for Design.

Patented Apr. 1, 1919.

Application filed February 19, 1918. Serial No. 218,175. Term of patent 14 years.

To all whom it may concern:

Be it known that I, WILLIAM S. HARLEY, a citizen of the United States, residing at Milwaukee, in the county of Milwaukee and State of Wisconsin, have invented a new, original, and ornamental Design for Motor-Cycle Frames, of which the following is a specification, reference being had to the accompanying drawing, forming part thereof.

The figure is a perspective view of a motorcycle frame, showing my new design.

I claim:

The ornamental design for a motor-cycle frame, as shown.

In testimony that I claim the foregoing I have hereunto set my hand at Milwaukee, in the county of Milwaukee and State of Wisconsin.

WILLIAM S. HARLEY.
